Charles Lorber,
BY *J. Clarkson*
ATTORNEYS.

UNITED STATES PATENT OFFICE.

CHARLES LORBER, OF BLOOMFIELD, NEW JERSEY.

KEY CASE.

Application filed February 14, 1928. Serial No. 254,182.

This invention relates to improvement in cases for keys and the like and, more particularly to such cases wherein the keys are supported in snap hooks and these hooks are 5 swingingly and swivelly mounted on a plate at the top of the case.

More particularly the invention relates to an improvement on my prior Patent 1,623,627, patented April 5, 1927, the hook here shown 10 being illustrated, described and claimed in my copending application for patent, Serial Number 289,118, filed June 29, 1928.

One important object of the present invention is to provide an improved combination 15 of supporting plate and swinging member with a novel key hook swiveled to the latter.

A second important object of the invention is to provide an improved combination of the above case wherein the key hooks may 20 not only swing and swivel but may also slide laterally of the case to thus enable a selected hook to be more readily separated from its fellows.

A third important object of the invention 25 is to provide a novel and improved form of key hook itself.

With the above and other objects in view as will be hereinafter apparent, the invention 30 consists in general of certain novel designs of construction and combinations of parts hereinafter fully described, illustrated in the accompanying drawings and specifically claimed.

In the accompanying drawings like characters of reference indicate like parts in the several views, and:

Figure 1 is a perspective view of the key case embodying the invention, the flaps of the case being shown in open position.

Figure 2 is an inside elevation of the upper part of such a case in its modified form.

Figure 3 is a section on the line 3—3 of the upper part of Figure 1.

Figure 4 is a section on the line 4—4 of Figure 2.

Figure 5 is an enlarged detail view showing the key hook itself in side elevation.

In both forms of the device there is provided a case forming member preferably of leather or other like suitable material and having a central back portion 10 and side flaps 11 foldable on the inside of the back portion in overlapping relation and capable of being secured in folded position by snap button elements 12. To the upper part of this key

case is secured by suitable rivets 13 a plate 14 and in the form shown in Figure 1 the plate 14 is provided at its upper edge with a series of slots, the material of the upper edge between the slots being bent to form a 60 series of eyes 15 wherethrough passes a supporting bar or rod 16 on which, in each slot, is mounted a ring 17 having a depending neck 18 which passes through a suitable opening in the eye 19 of a key hook and has its 65 lower end enlarged as at 20 so that while the key hook may swivel free on the neck 18 it cannot become detached therefrom. The eye portion of this hook is arcuate for the upper part of its extent and the material from which 70 the hook is made is reversely curved as at 21 to merge into a straight back portion 22. This back portion merges into a substantially semi-circular bight 23 which in turn extends into the straight bill 24 which converges to 75 toward the back 22 at the reverse curve 21. The other end of the material extends in a tangent from the curved portion of the eye 19 as at 25 and lies flat against the inner side of the back 22 adjacent the eye, the end of the bill 80 24 engaging this back engaging portion of the eye and terminating in an outwardly curved end 26. With this type of hook it will be seen that the bill aids in holding the end of 85 the eye against the back.

In the form shown in Figure 2 the plate 14 is provided at each upper corner with an eye 27 and a rod 28 extends between these eyes, the rod being free from the plate between said eye. The same type of rings 17 is 90 applied to this rod 28 and these rings cannot only turn on the rod but can also slide there along so that one hook may be separated laterally from the fellows by pushing the remainder of the hooks to the right or left as the case may be. In both of these types the same 95 form of hook is used, this form being indicated in general in Figures 1 and 2 and 5 by the letter H, it being deemed unnecessary to encumber Figures 1 and 2 with reference characters indicating the particular portions of the hook as in Figure 5.

There has thus been provided a simple and efficient device of the kind described and for the purpose specified.

It is obvious that minor changes may be made in the form and construction of the invention without departing from the material spirit thereof. It is not, therefore, desired to confine the invention to the exact form here- 100 105 110 115

in shown and described, but it is desired to include all such as properly come within the scope claimed.

Having thus described the invention, what is claimed as new, is:

1. In a key case, a supporting plate having a pair of tongues projecting from its upper edge at the ends thereof and bent to form a pair of widely spaced eyes projecting therefrom, a rod extending between said eyes, a series of rings slidably and rotatably mounted on said rod between the eyes, each of said rings having a projecting shank, and key hooks each having an eye swiveled on a respective shank and having the shank end extending into the eye and enlarged.

2. In a key case, a supporting plate having a pair of widely spaced eyes projecting therefrom, a rod extending between said eyes, a series of rings slidably and rotatably mounted on said rod between the eyes, each of said rings having a projecting shank, and key hooks each having an eye swiveled on a respective shank and having the shank end extending into the eye and enlarged, said rod being positioned sufficiently far in advance of the plate to permit said hooks to hang parallel to said plate and being free between said eyes.

In testimony whereof I affix my signature.

CHARLES LORBER.
